[57] ABSTRACT

A method of fabrication and application of a small metallic clip which is utilized to attach tympanoplasty material securely into position during ear surgery is described.

METHOD OF SURGICALLY REPAIRING DAMAGED EAR DRUMS

BACKGROUND OF THE INVENTION

The invention to be described relates primarily to a method by which tympanoplasty grafting material can be securely fashioned within the ear surgery. For many years, the most popular method of grafting ear drums has been to place the grafting material on the lateral surface of the ear drum and pack it tightly into position. Because of difficulty with lateral grafting and, in general, better results obtained with medial grafting, the latter method has gained great popularity in the last 5 years. The one deficiency with medial grafting has been a lack of methods available to secure the position of a graft at surgery. Methods in the past have primarily utilized the support of the graft interiorly with pledgettes of reconstituted protein called Glefoam.

SUMMARY OF THE INVENTION

The invention provides some mechanical means be utilized to secure the position of tympanoplasty graft and has proved to be, a definite advantage manifested in increased great survival rates.

The FIG. 1 shows an open clip.

The FIG. 2 of the drawings shows in a perspective view a clip joining a graft to the annulus of the ear.

The small clips A utilized in the inventive concept are fashioned from No. 34 stainless steel wire which was wrapped about an 18 gauge suction needle, the resul-

tant "spring" was cut longitudinally. The resultant clips, better described as Microclips, see A, FIG. 1, were then flattened out and trimmed to a two-thirds full circle. The clip was then loaded in a Stapes prosthesis crimper D as in FIG. 2. As further denoted in FIG. 2, the pars tensa and/or annular remnant, illustrated as B in FIG. 2, is suitably exposed. The tympanoplasty graft C is then positioned through a posterior tympanotomy incision so that it is medial to the annulus and malleus. A conventional 20 gauge sucker or vacuum means is then used to bring the leading edge of the graft to the edge of the perforation or annular remnant area of the tympanic fibrous annulus B. The clip A is then applied around the annulus and graft in locations corresponding to the 1, 3 and 6 o'clock positions.

I claim:

1. The method of repairing damaged ear drums by tympanoplasty grafting comprising the steps of, exposing the area of the pars tensa and annular remnant by 20 a posterior tympanotomy incision, positioning the graft on the tympanic fibrous annulus so that it is medial to the annulus and malleus tissue, attaching said graft to said annulus by inserting through the tissues of the junction of the graft and the annulus, at least three 25 metal surgical micro-clips of substantially C-shape and of a diameter of approximately 1.5 m.m. at positions near the 1, 3 and 6 o'clock locations, mechanically closing said clips to join and hold the enclosed tissues, and permitting the junction to heal to an attachment.
